UNITED STATES PATENT OFFICE

ARTHUR R. GROSS, OF ST. PAUL, MINNESOTA, ASSIGNOR, BY MESNE ASSIGNMENTS, TO TRUSSBILT STEEL DOORS, INC., OF ST. PAUL, MINNESOTA, A CORPORATION OF DELAWARE

HOLLOW SHEET-METAL UNIT

Application filed September 15, 1927. Serial No. 219,643.

My present invention relates to a hollow sheet metal unit having an internal metal reinforcement spot welded thereto, and has for its object the provision of such a unit that is of relatively light weight, strong and rigid.

Said invention has for its further object the elimination or reduction to a minimum the shrinkage, warpage or other distortion in its side plates due to heat produced during the 10 spot welding of the metal reinforcement to the unit proper. By preventing or reducing to a minimum shrinkage, warpage or distortion in the side plates of the unit, a large amount of hand work, such as stretching by 15 heat process, polishing and the like, to bring the sides of the unit back to their original shape, is eliminated, thus materially reducing the cost of manufacture, and at the same time producing a unit that does not require filling 20 by a heavy coat of finishing material such as paint, enamel or the like, to fill the uneven surfaces thereof in order to make a smooth exterior finish. Such filling is highly objectionable for the reason that if it cracks, peels, 25 or is otherwise defaced, it is practically impossible to refinish the same properly without sending the same back to the factory, which is very expensive.

The invention, while intended for general 30 use in the construction of table tops, and panels in building structures, car bodies and the like, is especially well adapted in the construction of doors and is so illustrated and described in the present application.

To the above end, generally stated, the 35 invention consists of the novel devices and combinations of devices hereinafter described and defined in the claims.

In the accompanying drawings, which 40 illustrate the invention, like characters indicate like parts throughout the several views.

Referring to the drawings:

Fig. 1 is a view partly in side elevation 45 and partly in vertical section taken substantially at the transverse center of the door;

Fig. 2 is an end view of the improved door;

Fig. 3 is a fragmentary view in horizontal section taken on the line 3—3 of Fig. 1, on an 50 enlarged scale; and

Fig. 4 is a fragmentary transverse vertical section taken on the line 4—4 of Fig. 3.

The numeral 5 indicates a hollow sheet metal unit or door comprising a pair of duplicate laterally spaced plates 6, the longitudinal edge portions of which are bent laterally toward each other and connected by joints 7 to form the longitudinal edge portions of said door. The ends of the door 5 are closed by channel end pieces 8 fitted therein with their flanges turned outward and spot welded at 9 to the sides of the plates 6. Longitudinal slots are formed in each end of each end piece 8 to afford liquid-filling and drain holes 10. These holes 10 also permit 60 the insertion of fastening devices into the door 5 for use in handling the same during the process of treating or finishing the door, as disclosed and broadly claimed in application executed of date August 31, 1927, and 65 entitled "Hollow sheet metal units and process of producing the same".

Within the door 5 is a truss structure 11 for the plates 6 and comprises a corrugated sheet metal plate. The apexes 12 of its corrugations are truncated or flat and alternately and directly engage the inner faces of the plates 6 and are spot welded thereto at 13. The apparatus used in spot welding the truss structure 11 to the plates 6 is disclosed and 75 broadly claimed in my co-pending application entitled "Welding apparatus", filed July 2, 1927, under Serial No. 203,236.

The longitudinal edge portions of the truss structure 11 are shaped to form portions of joints 7 and which joints are preferably of the type disclosed and broadly claimed in my co-pending application entitled "Metal door structure", filed June 13, 1927, under Serial No. 198,488. It will be noted that the truss 85 structure 11 terminates short of the end pieces 8 and leaves a shallow chamber 14 in each end of the door with which the respective ends of the tubular sections of the truss structure 11 formed by the corrugations 90 therein have communication and into which chambers the holes 10 open.

It is also highly important to note that the webs 15 of the truss structure 11 are 95 reversely oblique, straight and flat in cross 100

section. These webs 15 afford compression tension members that connect the two plates 6 and will not stretch, straighten or buckle under pressure or strains applied to the door 5.

As previously stated, the plates 6 are duplicates and their joints 7 are connected by the longitudinal sliding movements of one of the plates 6 in respect to the other. These joints 7 securely hold the plates 6 interlocked against movements in all directions transversely of the door. It is highly important to note that the sheet metal plate from which the truss structure 11 is formed is of a lighter gauge than the two plates 6 and, by reference to Fig. 3, it will be noted that there are illustrated co-operating inner and outer electrodes *x* and *y*, respectively, which may be used in connection with the above noted welding apparatus.

By reference to Fig. 3 it will be noted that the outer electrode *x* has a much larger contacting surface with the respective outer plate 6 than the inner electrode *y* has with the truss structure 11.

The peculiar construction of the truss structure 11 heretofore described, permits the use of a relatively thin metal sheet and at the same time gives the necessary strength and rigidity to the door 5 and reduces the weight thereof. The use of a relatively thin metal for the truss structure 11 also has another important function in that it will be heated much quicker than the respective relatively thick plate 6 and hence fuse with the metal in the inner face of said plate to form a spot weld before the outer face of said plate is distorted to any marked degree by the heat from the contacting electrode *x*.

The use of the relatively small electrode *y* contacting with the truss structure 11 and the co-operating relatively large electrode *x* contacting with the plate 6 further facilitates the heating of the truss structure 11 faster than the heating of the outer face of the plate 6 for the reason that the current passing through the electrode *y* to said truss structure is confined to a much smaller area than the current passing through the electrode *x* to the plate 6.

What I claim is:

1. A hollow sheet metal unit comprising a pair of laterally spaced side plates, the longitudinal edge portions of which are shaped to form the edges of the unit, channel end pieces fitted into the ends of the unit with their flanges turned outward and spot welded to the sides of the unit, a metal reinforcement in the unit comprising a corrugated metal sheet welded at its apexes to the sides of the unit and affording a plurality of open-ended tubular sections that extend longitudinally of the unit and terminate short of the end pieces to afford a chamber

at each end of the unit, and liquid-filling and drain holes in the end pieces.

2. A hollow sheet metal unit comprising a pair of laterally spaced sides, the longitudinal edges of which are shaped to form the edges of the unit, channel end pieces fitted into the ends of the unit with their flanges turned outward and spot welded to the sides of the unit, a metal reinforcement in the unit comprising a corrugated metal sheet having flat apexes, alternately and directly engaging the sides of the unit and spot welded thereto, said reinforcement dividing the unit into a plurality of tubular sections extending longitudinally of the unit and terminating short of the channel end pieces to afford a compartment in each end of the unit, and liquid-filling and drain holes in the end pieces.

3. A hollow sheet metal unit comprising a pair of spaced stiff metal side plates, and an internal reinforcement for said unit comprising a relatively light gauge corrugated metal sheet, the apexes of the corrugations being truncated and fused to the inner surfaces of said side plates and the webs of the corrugations being reversely oblique and straight in cross-section, said corrugated metal sheet being of a sufficiently lighter gauge than the side plates that fusion thereof may be accomplished without altering the outer surface of the side plates, whereby maximum strength and rigidity is effected with the minimum of reinforcing material and surface contact with the side plates.

4. A hollow sheet metal unit comprising a pair of spaced stiff metal side plates and an internal reinforcement for said unit comprising a relatively light gauge corrugated metal sheet fused to the inner surfaces of said spaced side plates, said corrugated metal sheet being of a sufficiently lighter gauge than the side plates that fusion thereof may be accomplished without altering the outer surface of the side plates.

5. A hollow sheet metal unit comprising a pair of laterally spaced side plates, the longitudinal edge portions of which are bent laterally and permanently connected together, channeled end pieces closing the ends of the unit, and a metal reinforcement in the unit spaced from the end pieces and comprising a corrugated metal sheet welded at its apexes to the sides of the unit providing longitudinally extending tubular sections having communication one with the other adjacent the ends of the unit.

In testimony whereof I affix my signature.
ARTHUR R. GROSS.
